UNITED STATES PATENT OFFICE

124,996

DESIGN FOR A SIGNAL HORN UNIT OR
SIMILAR ARTICLE

George H. Curtis, Melrose, Mass., assignor to
Heinze Electric Corporation, Lowell, Mass., a
corporation of Michigan

Application June 17, 1940, Serial No. 93,051

Term of patent 7 years

To all whom it may concern:

Be it known that I, George H. Curtis, a citizen of the United States and a resident of the city of Melrose, in the county of Middlesex and State of Massachusetts, have invented a new, original, and ornamental Design for a Signal Horn Unit or Similar Article, of which the following is a specification, reference being had to the accompanying drawing, forming a part thereof.

On the drawing:

Figure 1 is a perspective view of the signal horn unit showing my new design; and

Figure 2 is a plan view thereof.

I claim:

The ornamental design for a signal horn unit, or similar article, as shown.

GEORGE H. CURTIS.
